(57) **CLAIM**

The ornamental design for a data logging device having tethered data communication interface, as shown and described.

DESCRIPTION

FIG. 1 is a perspective view of a data logging device having tethered data communication interface stowed;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof;

FIG. 8 is a front view thereof, with the tethered communication interface extended; and,

FIG. 9 is a rear view thereof.

The broken-line disclosure in the views represents portions of the article in which the design is embodied but which form no part of the claimed design.
